UNITED STATES PATENT OFFICE

ERICH F. JAHNKE, OF APPLETON, WISCONSIN

SPEAKING CLOCK

Application filed November 12, 1926. Serial No. 148,044.

This invention relates to a speaking clock, the general object of the invention being to provide a phonographic attachment for the clock which will call out the hours and 5 half-hours in place of the clock striking the hours so that it is not necessary for one to stop and count the strikes in order to determine the hour being struck.

Another object of the invention is to provide 10 means for resetting the reproducer of the record after the end of the record has been reached by the needle so that the machine will start over again.

This invention also consists in certain other 15 features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a perspective view of the improved clock.

Figure 2 is a horizontal sectional view through the phonographic part of the same.

30 Figure 3 is a side view, with parts broken away.

Figure 4 is an enlarged fragmentary view with parts in section, showing the movable joint between the reproducer arm and the sound box.

35 Figure 5 is a section on line 5—5 of Figure 2.

Figure 6 is a section on line 6—6 of Figure 5.

40 Figure 7 is a section on line 7—7 of Figure 2.

Figure 8 is a view showing how the movement of the turntable of the phonograph is controlled by the clock mechanism.

45 Figure 9 is a view of the stop lever of such means.

Figure 10 is a bottom plan view of the turntable.

Figure 11 is an edge view of the same.

50 Figure 12 is a face view of portion of the record used with the device.

In these views, 1 indicates the casing of the clock and 2 indicates the casing of the phonographic arrangement which forms a base for the casing 1. The clock may be made of the usual or any desired construction, and in carrying out my invention, I cut off the arm 3 of the alarm releasing means, as such alarm means are not used. This arm 3 is connected by a link 4 with a lever 5 which is pivoted to a bracket 6 connected with the inner wall of the casing 2 so that the said lever will be rocked by the movement of the arm 3. A spring 7 tends to hold the lever 5 with its upwardly extending outer end against the bottom of the turntable 8 of the graphophone which is arranged in the casing 2. This table 8 has an arc-shaped strip 9 connected to its bottom in such a manner that the projecting part of the lever 5 will first pass over the tapered part of the strip, which will tend to check the movement of the turntable and then the lever will engage a depending part 10 of the member 9 and thus further movement of the turntable will be prevented until the lever has been moved to release the table.

The record 11 has its reproduction grooves 12 so formed that the outermost groove 12 will reproduce the words "One o'clock", the next groove will reproduce the words "One thirty" or "Half past one", the next groove will reproduce the words "Two o'clock" and so on to the end of the record, the end groove reproducing the words "Twelve thirty". As shown in Figure 12, plain grooves are formed in the record before each reproducing groove so that the turntable can make several revolutions before the needle of the reproducer 13 will strike the reproducing groove. This will enable the turntable to reach its full speed before the needle strikes the reproducing groove. The spindle of the turntable is provided with a key for engaging a keyway 14 in the table and a keyway 15 in the record and the upper end of the spindle is threaded to receive a nut 16 so that the turntable and record are held on the spindle by the nut. By using the key and the keyways, there is no danger of the record being misplaced on the table and it must be properly placed on the table when being put thereon so that the

reproducing grooves will be in a proper position relative to the operation of the brake by the clock mechanism.

- In order to bring the reproducer arm back 5 to its starting point after the needle has passed over the record and at the end of twelve hours, I place a roller 17 in the reproducer arm 18 and place a track forming strip 19 under the roller, one end of this strip being 10 pivoted to a bracket 20 connected with the phonographic casing and its other end being slotted, as at 21, to engage an eccentric pin 22 on a disk 23 which is fastened to a shaft 24 of a spring motor 25. The disk 23 has a 15 projection 26 thereon which is adapted to be engaged by a spring latch 27, the spring of which is shown at 28 and this spring latch has an arm 29 depending therefrom which is adapted to be struck by the reproducer arm 20 at the end of the record so that the said reproducer arm will swing the latch into inoperative position, thus releasing the disk 23 and permitting it to be rotated by the spring motor 25 through means of the shaft 24. 25 This will cause the eccentric pin to move the track forming strip 19 upwardly into a tilted position where it will engage the roller 17, thus moving the reproducer arm upwardly so as to move the needle of the reproducer off 30 the record. As the track forming strip is in a tilted position, the weight of the reproducer arm and its attached parts will cause the arm and roller 17 to run down the track forming strip 19 until the arm strikes the stop 30 on 35 the said strip, which stops the arm with the needle at the beginning of the record. At this time, the disk 23 will have made a complete revolution so that the track forming strip will be lowered again so that the needle can 40 engage the first groove in the record and further movement of the disk will be prevented by the latch 27 engaging the stop 26. Thus each time the needle reaches the end of the record, the parts will be returned to their 45 starting position.

The motor 25 has its spring 25' wound by the turning of a shaft 31 by a key introduced through a hole 32 in the casing, the said shaft entering the motor casing and having the 50 spring 25' attached to its inner end. The other end is attached to the casing of the drum 25 which is connected with the shaft 24. Ratchet mechanism 32' is associated with the shaft 31. I also provide governor means 33 55 for the motor 25, as shown in Figure 5.

The shaft for the motor 34 of the graphophone, shown at 36, passes through the casing 2 so that it can be wound by a key.

The reproducer arm is connected to a section 60 36 by the universal joint 37 which is pivotally connected together by the pin 38 so that the arm can rock about a horizontal axis to enable it to be lifted at the end of the record and returned to its starting position. 65 The section 37 is rotatably mounted in a

vertical part 39 which is stationary and which is in communication with the pair of horns 40, each horn opening out through a window 41 in the casing 2.

From the foregoing it will be seen that 70 each time the clock parts reach the hour position and the half-hour position, the arm 3 will be raised so that the stop lever 5 will be moved to a position where it will release the turn-table of the graphophone so that 75 the table will be rotated by its motor and thus cause the needle to engage a reproduction groove so that the graphophone will announce the hour and half-hour. Of course, if desired, the graphophone could announce 80 the quarter hours. When the arm 3 drops, due to the movement of the clock mechanism, the stop lever 5 will be moved back to its operative position and thus stop the turn-table. This will continue until the needle reaches the 85 end of the record, when the reproducer arm, striking the depending part 29, will move the latch 27 to inoperative position so that the disk 23 will be rotated by its spring motor to raise the track part 19 to cause the reproducer arm to move back to its starting position. This movement will take place every twelve 90 hours, as will be understood. It will be seen that the only thing necessary to keep the phonographic announcer in operation is to 95 wind the springs of the motors 25 and 34. Of course, a new record will have to be put in place after the old one has become worn and the needle will have to be renewed from time to time.

It is thought from the foregoing description that the advantages and novel features of our invention will be readily apparent.

I desire it to be understood that I may make changes in the construction and in the 105 combination and arrangement of the several parts, provided that such changes fall within the scope of the appended claim.

What I claim is:—

A stop mechanism for a phonograph turntable, including a stop lever for controlling the rotary movement of the table, and an arc-shaped rib on the bottom of the turn table for engaging one end of the lever, said rib gradually increasing in thickness from its 110 forward to its rear end, and a depending part on the rear end of the rib, whereby the engagement of the lever by the rib will check the movement of the turn table, and the engagement of the depending part with the latter will stop the turn table.

In testimony whereof I affix my signature.
ERICH F. JAHNKE.
